UNITED STATES PATENT OFFICE.

WILLIAM H. SARGENT, OF LYNN, MASSACHUSETTS.

MACHINE FOR OPENING AND SOFTENING COUNTERS OF SHOES.

1,192,463.

Specification of Letters Patent. Patented July 25, 1916.

Application filed February 21, 1916. Serial No. 79,655.

To all whom it may concern:

Be it known that I, WILLIAM H. SARGENT, a citizen of the United States, residing at Lynn, in the county of Essex, State of Massachusetts, have invented a certain new and useful Improvement in Machines for Opening and Softening Counters of Shoes, of which the following is a specification, reference being had thereto to the accompanying drawings.

The general object of the invention is to provide means for opening or spreading the counter of a new boot or shoe to facilitate trying the latter on as well as avoid pressure against opposite sides of the wearer's heel, and also for softening the counter to render the same easy and comfortable to the wearer.

In the state in which new boots and shoes are placed on sale in retail stores or shops, the counter of a boot or shoe has been molded or shaped to so small a width in the upper portion thereof that the opening between the opposite sides is too narrow to permit the ready insertion of a person's heel, and is so narrow that if the said heel is forced down into place the pressure of the hard upper portion of the counter against the opposite sides of the heel tends to produce discomfort and pain, with chafing and blistering. In practice a salesman, on taking a pair of shoes from a box or carton for the purpose of fitting a customer, manipulates each shoe in turn to open and soften its counter. The usual method is to hold a shoe firmly in one hand and apply strong pressure by the base of the palm of the other hand to the back of the counter of the shoe so as to crush the counter inwardly, thereby spreading it, the manipulation being continued until the counter has been broadened out and softened to the extent which he deems proper. In performing this manipulation it often occurs that the upper of a shoe is separated from the sole around the base of the counter, leaving an opening or crack, and in the case of high-heeled women's shoes it happens with great frequency that the heel is split away from the sole at the back of the heel. These injuries due to handling by salesmen result in large numbers of shoes being returned from the stores to the factories to be fixed in good shape again. This entails very considerable expense and more or less inconvenience.

The invention consists in a machine

which is so contrived as to enable the opening and softening operations to be performed better and more conveniently than by hand manipulation, and without any liability to injure a shoe in the foregoing respects.

The drawings show a convenient embodiment of the invention, which latter is not restricted to this particular mode of embodiment.

In the drawings, Figure 1 is a side elevation of a machine comprising the said embodiment. Fig. 2 is a front elevation of the said machine. Fig. 3 is a plan view thereof. Fig. 4 is a side elevation of the machine with a shoe applied thereto, illustrating the mode of operation, the handle of the operating lever being broken off. Fig. 5 is a view looking from the right hand side in Fig. 4, parts of the operating lever and shoe being broken away.

Having reference to the drawings, a machine embodying my invention comprises two presser-members, one of which is adapted to be introduced within the counter of a shoe, means for so supporting the presser-members as to permit the top of a shoe to be passed in between them and in manner providing for relative movement toward and from each other, and means by which at the will of the operator they may be closed together upon the interposed back of the shoe counter.

The presser-members of the illustrated embodiment of the invention comprise an inside block 1 and an outside block 2. The inside block 1 is adapted to be inserted within a shoe counter, *as*, Figs. 4 and 5, so as to make contact with the interior of the latter, and the outside block 2 is adapted to act against the exterior of the counter. The supporting means consists of a stand 3 having a lower projecting arm 3^a on which one presser-member is mounted, and an upper projecting arm 3^b on which the other presser-member is mounted, the opening between the said upper arm and the lower arm and stand being of sufficient length from front to rear to accommodate the top of a shoe which has been placed upon the lower presser-member. In this instance, one of the presser-members is mounted fixedly upon its supporting arm, and the other is mounted movably upon its supporting arm in a manner providing for movement toward and from the first. The fixed presser-member in

this case is the lower one, 1, it being fixed in position upon the projecting arm 3^a, and the movable presser-member is the upper one, 2, it being mounted in connection with the upper arm 3^b in a manner permitting it to have movement relative to such arm. The stand 3 is adapted to be mounted upon the top of a table or counter, as 4, or upon a shelf, near one edge of the particular support that may be utilized, so that the arm 3^a shall project beyond the said edge as indicated in Figs. 1, 3, and 4 of the drawings. The extent of the projection of the arm 3^a and block 1 beyond the edge of the support 4 is sufficient to enable a shoe to be passed over the said block and arm until the shoe counter is properly applied to the block as in Fig. 4. The particular means of mounting the block 2 movably in connection with the supporting arm 3^b comprises pins 5, 5, having their lower ends connected fixedly with the said block and their stems fitted to holes in the outer end of the said arm 3^b and surrounded above the latter by expanding spiral springs 6, 6, which are confined between nuts 7, 7, upon the threaded upper portions of the stems and the bottoms of spring-receiving sockets that are formed in the upper portion of the arm. These springs serve to support block 2 normally in elevated position in contact with the under side of the outer end of the supporting arm 3^b, while leaving such block free to be moved toward the fixed block 1. In the movement of the block 2 toward and from the block 1 the pins guide the block 2 in its movements. The means for operating the movable block 2 comprises, in this instance, an operating lever 8 having a handle-portion 8^a. This lever is mounted pivotally at 8^b in a slot made in the outer end of the supporting arm 3^b, and it is formed with a short arm 8^c carrying an anti-friction roll 8^d which makes contact with the upper surface of the block 2 midway between the pins 5, 5. Movement of the lever forward and downward around its pivot 8^b will cause the anti-friction roll 8^d to transmit pressure to the top of the block 2 and to bear down the said block toward the block 1, the said anti-friction roll traveling rearwardly along the top of the block as the lever turns and the block descends. When the lever is freed or given an upward and rearward movement the springs 6, 6, will raise the block 2 to its original or normal position, and usually will act through the block to return the operating lever to its normal position.

The two presser-members or blocks 1, 2, are shaped for coöperation with each other and for action in connection with the counter of the shoe so that when a shoe is applied to the lower block 1, as in Figs. 4 and 5, with its counter surrounding the said block and the interior surface of the back

of the counter resting upon such block, the said block 1 will support the counter at opposite sides of the apex of its back, to or substantially to the top of the counter, and pressure applied by the presser-member or block 2 against the exterior of the back of the counter will flatten the curvature of the said back, spreading the sides thereof apart, and bend and work the materials comprised in the counter. Thereby the counter will be opened or spread and the hard counter-stiffener will be softened and rendered flexible.

Preferably, the acting portion of the inside block or presser-member 1 is concaved and that of the outside block or presser-member 2 is convex, in order that when the two blocks or presser-members are caused to close together upon an interposed counter having its interior surface resting upon the opposite horns of the concaved face of the block 1, the effect may be to reverse the curvature of the back of the counter, in this respect reproducing the action which takes place when a salesman crushes in the counter of a shoe by hand as at present.

What is claimed as the invention is:

1. A machine for opening and softening counters of shoes, comprising an inside block or presser-member adapted to receive upon and around it the counter of a shoe and to support the counter at opposite sides of its apex to or substantially to the upper edge of the counter, an outside block or presser-member adapted to act upon the exterior of the back of such counter and through co-operation with said inside block or presser-member flatten the curvature of the back of the counter so as to open or spread the counter laterally and render it flexible, and means for producing relative movement of approach and separation of the said blocks or presser-members.

2. A machine for opening and softening counters of shoes, comprising an inside block or presser-member having a concave working face adapted to receive upon and around it the counter of a shoe and to support the counter at opposite sides of its apex to or substantially to the upper edge of the counter, an outside block or presser-member adapted to act upon the exterior of the back of such counter and through co-operation with said inside block or presser-member flatten the curvature of the said back so as to open or spread the counter laterally and render it flexible, and means for producing relative movement of approach and separation of the said blocks or presser-members.

3. A machine for opening and softening counters of shoes, comprising an inside block or pressure-member adapted to receive upon and around it the counter of a shoe and to support the counter at opposite sides of its apex to or substantially to

the upper edge of the counter, an outside block or presser-member having a convex working face adapted to act upon the exterior of the back of such counter and 5 through coöperation with said inside block or presser-member flatten the curvature of the said back so as to open or spread the counter laterally and render it flexible, and means for producing relative movement of

approach and separation of the said blocks 13 or presser-members.

In testimony whereof I affix my signature in presence of two witnesses.

WILLIAM H. SARGENT.
